UNITED STATES PATENT OFFICE.

FRANK J. MATCHETTE, OF MILWAUKEE, WISCONSIN.

VACUUM-SWEEPER.

1,020,104.

Specification of Letters Patent. Patented Mar. 12, 1912.

Application filed June 12, 1909. Serial No. 501,707.

To all whom it may concern:

Be it known that I, FRANK J. MATCHETTE, a citizen of the United States, residing at Milwaukee, in the county of Milwaukee and 5 State of Wisconsin, have invented certain new and useful Improvements in Vacuum-Sweepers, of which the following is a specification, reference being had to the accompany drawing, forming a part therof.

10 This invention relates more particularly to tools for taking up and removing dust and dirt with an air draft from carpets, rugs and the like. Its main object is to simplify and improve the construction and operation of tools of this class, and it consists in the construction, arrangement and combination of parts as hereinafter particularly described and defined in the claims.

20 In the accompanying drawing like characters designate the same parts in the several figures.

Figure 1 is a plan view of a sweeper embodying the invention; Fig. 2 is a longitudinal section of the same on the line 2 2, Fig. 25 1; Fig. 3 is a transverse section cutting the tubular shank lengthwise on the line 3 3, Figs. 1 and 2; and Fig. 4 is an end view of the tubular sweeper head.

The sweeper comprises an open frame or 30 shoe *a*, a tube *b*, and a tubular shank *c* in which the tubular handle or arm *d* for operating the sweeper and connecting it with a pump or other vacuum producing means, is removably fitted.

35 The frame or shoe *a* may be cast as shown, in one piece, with parallel side bearing pieces *e* connected at the ends by arches *f* and located at a distance from the tube *b*. The arches are formed in their inner and 40 opposing sides with curved grooves *g* concentric with the alined openings in the arches. The tube *b*, which is preferably made of sheet metal or seamless tubing, is of cylindrical form and has a longitudinal 45 slot in the under side extending from end to end, the edges of the metal next to the slot being flanged or bent inwardly and forming with the sides of the tube, cleaning lips *h* around or underneath which the air 50 has to pass to enter the tube.

i is a segmental sleeve in which the tube *b* is fitted, and which in turn is fitted at the ends into the arches *f*, in which it is secured with the tube by pins *j* or other suitable 55 means. The shank *c* terminates at one end in a laterally extended concave bearing *k*,

which is fitted to turn upon the sleeve *i* and is held and guided at the ends in the grooves *g* so as to maintain a close working fit between said bearing and said sleeve. The 60 opposite end of the shank is counterbored and provided as shown in Fig. 3, with an elastic split coupling ring *l*, the normal internal diameter of which is slightly smaller than the external diameter of the tubular 65 handle or arm *d*. The coupling ring *l* is loosely confined in the counterbore of the shank by a ring *m*, which is forced into or otherwise secured in place in the shank. Disks *n* and *o* are fitted and secured in the 70 ends of the tube *b*, the disk *o* being formed with an opening *p* which affords access to the interior of the tube and means for removing obstructions therefrom. This opening is normally closed by a pivoted cover *q*. 75 The disks are cut away or recessed as shown in Figs. 2 and 3, next to the slot in the under side of the tube, thus affording restricted openings at those points for the admission of air into the tube. The effect of 80 these openings is to admit a small excess of air at points remote from the tubular shank *c* and thus make uniform the air draft or current throughout the length of the 85 sweeper.

The tube *b* and the sleeve *i* are formed in the upper part thereof with an opening or port *r* through which the interior of the tube is in constant communication with the passage in the tubular shank *c*, whatever the 90 angular position of the arm or handle *d* may be.

The lips *h* along the sides of the slot in the under side of the tube, project slightly below the adjacent edges of the sleeve *i* and 95 the bearing pieces *e* of the shoe, so as to sink into a carpet, rug or other fabric, in the operation of the sweeper thereon, and thus cause the air as it rushes around or underneath said lips into the tube through the 100 slot in the underside thereof, to more effectively dislodge and remove dust and dirt from the carpet, rug or other fabric.

In the operation of the tool, the handle or arm *d* swings freely with the shank *c* 105 around the tube *b* in a plane at right angles to its axis, assuming any position or angle relative to the plane of the bearings *e* of the shoe most suitable and convenient for the operation of the tool under varying conditions. The bearings *e* of the shoe being located at some distance from and on oppo-

site sides of the tube *b*, carry the tube with the slot on the under side thereof in the proper relation to the work, whatever position or angle the handle or operating arm 5 may assume.

For sweeping under low furniture, fixtures or other objects, the handle or operating arm may be swung down close to the floor as shown in Fig. 3, so as to require 10 very little head room.

Various changes in the details of construction may be made without departing from the principle of the invention.

I claim:

15. 1. In a vacuum sweeper the combination of a tube having a longitudinal slot in the under side, and a port in the upper middle portion, a shoe having bearings on opposite sides of and approximately parallel with said tube and connected at the ends by arches in which the tube is fitted and secured, and a tubular shank having a transverse concave bearing fitted to turn upon said tube and guided at the ends in said arches, with 20 25 the passage in the shank in communication with the port in said tube.
2. In a vacuum sweeper the combination of a tube having closed ends, a longitudinal slot in the under side and a port in the upper middle portion, a shoe having bearings on opposite sides of said tube and approximately in the plane of said slot and connected at the ends by arches in which said tube is secured and which are formed in 30 35 their inner sides with grooves concentric with the tube, and a tubular shank terminating at one end with a concave bearing which is fitted upon said tube over the port therein and has tongues at the ends fitting into and 40 guided in the grooves in said arches.
3. In a vacuum sweeper the combination of a shoe having bearing pieces connected by arches, a metal tube having a longitudinal slot in the under side, the edges of the metal next to the slot being flanged inwardly, a segmental reinforcing sleeve fitted 45 over the middle portion of the tube and secured therewith in the arches of the shoe, and a tubular shank terminating at one end 50 in a concave bearing which is fitted to turn on said sleeve and is guided concentric therewith in said arches, the tube and sleeve being formed with a port through which the 55 passage in the shank communicates with the interior of the tube.
4. In a vacuum sweeper the combination of a shoe having bearing pieces connected by

arches, a segmental sleeve fitted and secured in said arches, a metal tube fitted and secured in said sleeve and having a longitudinal slot in the under side, the edges of the metal next to the slot being flanged inwardly and forming with the adjacent sides of the tube cleaning lips which project below the adjacent edges of the sleeve, and a 60 65 tubular shank terminating at one end in a transverse concave bearing which is fitted to turn on said sleeve and is guided concentric therewith in said arches.

5. In a vacuum sweeper the combination 70 of an open frame or shoe having side bearing pieces connected at the ends by arches which are formed with grooves in their inner and opposing sides, a segmental sleeve fitted in said arches, a cylindrical tube fitted in and 75 secured with said sleeve in the arches and between the bearing pieces of said shoe and having closed ends and a longitudinal slot with turned edges along the under side, and a tubular shank terminating at one end 80 in a laterally extended concave bearing fitted to turn on said sleeve and guided at the ends in the grooves of said arches, the tube and sleeve being formed with a port in position to communicate with the passage in 85 said shank.

6. In a vacuum sweeper the combination 90 of a tube having a longitudinal slot in the under side, a shoe fixed to said tube and having bearings on opposite sides thereof and at a distance therefrom, the tube along the sides of said slot extending below said 95 bearings, and a tubular shank having a hinge or pivot connection with the tube and communicating with the interior of the tube through a port therein.

7. In a vacuum sweeper the combination 100 of a tube having a longitudinal slot in the under side and restricted openings in the ends next to the slot, a shoe fixed to said tube and having bearings on opposite sides thereof and at a distance therefrom, the tube along the sides of the slot extending below said 105 bearings, and a tubular shank having a hinge or pivot connection with the tube and communicating with the interior of the tube through a port therein.

In witness whereof I hereto affix my signature in presence of two witnesses.

FRANK J. MATCHETTE.
